UNITED STATES PATENT OFFICE

PERLEY R. GLASS, OF WAYLAND, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

METHOD OF AND MACHINE FOR FOLDING SHEET MATERIAL

Application filed August 9, 1923. Serial No. 656,557.

This invention relates to methods of and machines for folding sheet material and is herein set forth in its application to the folding of the margins of the covers of book cases 5 the board or boards upon which the covers are mounted.

In the manufacture of memorandum books, pocket-books and similar articles it is customary to attach to the board or boards by 10 means of paste a cover of leather or imitation leather the margins of which extend beyond the edges of the boards and then to apply paste to these margins and fold them over upon the adjacent margins of the boards. 15 The corners of the finished case may be rounded or square; and the manner in which they are cut and folded differs according to whether they are to be the one or the other. Hitherto, the folding operations have been 20 largely carried out by hand; and the general object of the present invention is to provide a machine which shall do away with hand folding.

According to the present invention, the machine is provided with mechanism for folding the margins along straight edges irrespective of the shape of the corners, and with two conveniently located mechanisms for folding the corners, one mechanism being 30 adapted to fold rounded and the other square corners. All that is required of the operator is to present the various localities of the work to the proper mechanisms, the necessity which formerly obtained for skill on the part of the 35 operator being largely obviated, and the time consumed greatly lessened.

In the manufacture of book cases having rounded corners, it is customary to prepare the boards with corners of the desired curvature and to prepare the covers with similarly rounded corners; and then, when the several corners of the cover are folded, to plait the margin of the cover at the localities in which it is folded over the rounded corners of 45 the boards. According to one feature of the present invention there is provided an edge guide having two faces arranged to include between them an angle and a folder having two faces arranged to include between them 50 a smaller angle. In the illustrative machine

the angle included between the faces of the edge guide is a right angle, since practically all book covers have four edges arranged in the form of a rectangle; and the faces of the folder include between them an acute angle. 55

The work, which consists of the usual boards and cover is presented corner-foremost to the guide in such manner that the margin of the cover at and adjacent to the corner is bent upwardly by the guide, and then the folder is 60 caused to move over the guide. Because the faces of the folder include between them an acute angle, the folding of the corner takes place progressively beginning at two points spaced from the apex of the corner and ending at the apex. This progressive folding or wiping of the margin of the cover over the board tends to the formation of regular plaits of substantially equal size. In order however to ensure a more precisely regular formation 65 of plaits as well as to aid in the proper presentation of the work to the guide, there may be provided a tool which cooperates with the folder to facilitate the formation of evenly spaced plaits. In the illustrative machine 70 this takes the form of a treadle-controlled tool provided with corrugations or ribs which is caused to drag along the inner face of the margin during the folding operation so as to aid in plaiting the corner of the cover at 75 the proper localities.

In the manufacture of books having square corners it is customary to use boards having square corners, and covers the corners of which have been cut off on an angle of about 85 135 degrees to the adjacent edges, the cutting-off being done to avoid objectionable thickness and unevenness in the finished folded corners. With the boards and covers shaped as indicated above and pasted together in the 90 usual manner, it is desirable, in order to secure a smoothly folded corner, first to fold the margin of the cover along one edge over the board, then to form a plait in a portion of the margin of the cover adjacent to the corner 95 and finally to fold the margin of the cover along the other edge over the board. According to another feature of the invention means are provided for forming this plait. In the 100 illustrative machine this means is associated

with and includes part of the mechanism for folding the straight edges. The edge guide is provided with a short face parallel to but offset from the long or main face so as to form a shoulder at their adjacent ends. After the entire margin along one edge of the cover has been folded by presenting it to the main face of the edge guide and causing a co-operating folder to operate, the folded margin adjacent to the corner is presented again, but this time to the offset face of the guide and held close up to the shoulder while the machine is operated once more. The presentation causes the formation of a pucker at the desired locality; and this pucker is pressed into a plait by the folder. The work is then turned 90 degrees and presented a third time to the main face of the edge guide, as in the first instance, to fold the margin at the adjacent side of the corner.

Considered in another aspect the invention provides a novel method of folding book covers, particularly those having rounded corners.

Referring now to the accompanying drawings,

Fig. 1 is a perspective of a machine in which the present invention is embodied and by the use of which the method may be practised,

Fig. 2 is a section on the line 2—2 of Fig. 1, Fig. 3 is a perspective of the two folders, the corner folder and the straight folder,

Fig. 4 is a perspective of the plaiting tool, Figs. 5, 6 and 7 are details in section showing different steps in the folding of a rounded corner,

Figs. 8 and 9 are perspectives respectively of a rounded corner before and after the folding operation has been carried out,

Fig. 10 is a perspective showing the shapes of the boards and cover when square corners are to be produced,

Figs. 11, 12, 13 and 14 are perspectives showing steps in the folding of a square corner.

Referring first to Figures 8 and 9, it will be noted that the work comprises the board 100, which may be of cardboard, pasteboard, heavy paper or any suitable material, and the cover 200 which may be of any flexible material and is commonly of leather or imitation leather. It will be understood that there are usually two boards placed with respect to the cover as shown in Figure 10 presently to be described. There are thus four straight edges and four corners to be folded. Where rounded corners are desired, the boards are cut with rounded corners and the cover with similarly rounded corners or with partially cut-off square corners, the margin of the cover projecting, as shown, beyond the edges of the boards; and when the corner of such a cover is folded over the corner of such a board, the corner of the cover should be plaited after the

manner indicated in Figure 9. With the machine of the present invention the work is first presented to corner-folding mechanism and then to mechanism for folding the straight edges, although, as will presently appear, if the work is small enough the corner-folding mechanism may operate to do all of the folding.

Referring more particularly to Figures 1 and 2 with occasional references to Figure 3, the corner-folding mechanism comprises a work support 15 which is generally triangular in shape, an edge guide 17 having two faces which include between them an angle equal to the angle included between the two straight edges of the board 100 which are adjacent to a rounded corner, and a folder 19 having two faces which include between them a smaller angle. The angularly arranged faces of the edge guide 17 are connected by a face which is curved to correspond to the curve of the rounded corner of the board 100; and the adjacent edge of the support 15 is curved in the same manner at the junction of its two angularly arranged faces, while the curve at the junction of the two angularly arranged faces of the folder 19 is a little more abrupt. In the operation of the machine, the work, in the condition shown in Figure 8 is placed upon the support 15 with the rounded corner of the board pushed as far as possible toward the edge guide 17 so that the projecting margin of the cover 200 is bent upwardly and extends above the guide. A treadle is then depressed, whereupon the folder 19 moves toward the operator to fold the margin of the cover over upon the board, after which the support moves upwardly to press the fold thus formed, it being understood that paste has previously been applied to the projecting margin of the cover to cause it to adhere to the board. Inasmuch as the angle included between the faces of the folder is smaller than that included between the faces of the edge guide, the folding operation takes place progressively beginning at two points spaced from the apex of the corner. In order to pucker and plait the corner regularly so that there may be no objectionable bunches in the finished corner, as well as to facilitate the proper presentation of the work to the edge guide, there is provided a combined work presser and plaiting tool in the form of a rod 21 having adjustably fastened to its lower end a plaiting-tool 23 comprising plurality of spaced ribs or corrugations 25 arranged to diverge slightly. Before the folder 19 begins its folding movement, the rod 21 is first brought down to press the work firmly against the support 15, as shown in Figure 5, and is then raised slightly. It is so mounted that it can be swung yieldingly to the left, as viewed in Figure 6, by the folder during the folding movement of that member. Dur-

ing the folding movement, therefore, it drags over the inner face of the margin of the cover and tends to crease the margin and thereby to cause the formation of properly spaced 5 puckers which are, by the subsequent upward movement of the support 15, pressed into plaits. It will be noted that the plaiting tool is located in the path of movement of the folder, that a portion of it extends above the 10 folder and overhangs the folder during the folding operation, and that the tool is yieldingly pressed against the inner face of the margin of the work so that the margin is frictionally gripped between the opposed 15 faces of the folder and the tool during said folding operation.

If the piece of work is small enough the folding of the four corners in the manner described will effect the folding of the four 20 straight edges as well, since portions of these edges are folded when the corners are folded. For the larger covers, however, it is preferable to provide additional mechanism for folding the straight edges. To this end there 25 is provided a work support 27, an edge guide to conform to the contour of the edges of the cover which extend between the corners (in the illustrative machine a straight edge guide 29) and a folder 31. The general mode 30 of operation of these parts is the same as that of the corner-folding parts which has been described above. The straight edge of a board is pushed as far as possible toward the straight guide 29 so that the projecting 35 margin of the cover extends upwardly, the folder moves over the guide to form the fold, and then the support rises to press the fold. It will be noted that the straight-edge folding mechanism is located at a level below 40 that of the round corner folding mechanism.

With this brief description of the mode of operation of the machine, a detailed description will now be given. The two work supports 15 and 27 are fastened respectively 45 by screws, two of which are shown at 33, 35, to a cross-head 37 which is vertically slidable in suitable guideways formed in the forward part of the frame 39 of the machine. Extending rearwardly from this cross-head 50 is a lug 41 to which is pivoted the lower end of a link 43 the upper end of which is pivoted to the forward end of a second link 45, the rear end of said link 45 being pivoted on a stationary rod 47. Also pivoted on the rod 55 47, or rather upon a small eccentric formed integral with it, as shown in Figure 2, is the hub of a lever 49 having at its outer end a fork to receive a cam 51 on the driving shaft 53. Integral with the hub of the lever are 60 two arms 55, 57 which extend respectively above and beneath the link 45. The lower arm 57 has formed in it a socket to receive a spring 59 which rests at its lower end upon a tension-varying screw 61 and bears with its 65 upper end against the under side of a collar

which is fast to or integral with a vertical rod 63, said rod bearing against the under side of the link 45. Threaded through the upper arm 55 is a screw 65 held from loosening by a lock-nut 67 and bearing against the upper side of the link 45. With this construction, when a revolution is imparted to the drive shaft 53, the lever 49 is oscillated about its pivot first to raise and then to lower the link 45 and with it the cross-head 37 and the work-supports 15 and 27. It should be noted that the raising of the work-supports takes place yieldingly through the spring 59 so that, during the pressing of a fold, there will be no danger of breaking any part; and, at the 75 same time, folds which differ somewhat in thickness may be pressed. If folds which differ considerably in thickness are to be pressed, the rod 47 may be turned to bring the eccentric upon it with a different angular position. In order to facilitate this adjustment there is fast to one end of this rod a handle 69 having integral with it a slotted segment 71 through the slot of which passes the stem of a cap screw 73. This screw is 80 threaded into the frame of the machine and carries between its head and the outer face of the segment 71 a washer and a coiled spring. When the cap screw is loosened, the handle 85 69 may be turned; at other times it is held 90 from movement by the cap screw, spring and washer.

The folders 19 and 31, like the work supports 15 and 27, are operated in unison. Depending from the under side of the folder 19 100 are two lugs 75 which receive between them a roll 77 carried at the upper end of an arm 79 which is pivoted at 81 to the frame of the machine.

Mounted on the arm 79 intermediate its ends is a cam roll 83 which runs on a cam 85 mounted on the driving shaft 53 at one side of the cam 51. A spring-pressed plunger 87, having at its outer end an anti-friction roll 89, urges the arm 79 to the right, as 110 viewed in Fig. 2, so as to hold the cam roll 83 in contact with the cam 85. The folder 19 is slidable in suitable horizontal guideways formed in the frame of the machine which compel the folder to move in a straight path and prevent lateral movement; and when a revolution is imparted to the driving shaft 53, the folder, owing to the shape of the cam 85, is first moved forward to form the fold, then held stationary while the fold is pressed, and then returned to initial position. The straight-edged folder 31 is also mounted in suitable guideways in the frame of the machine and partakes of the movements of the corner-folder 19. It is attached to the folder 19 (see Fig. 3) by studs 91 which extend upwardly into holes 93 in the folder 19 and downwardly into holes 95 in rearward extensions formed on the folder 31. The mechanisms for operating the folders and work 120 125 130

supports are constructed and arranged first to cause the folders to move forward (to the left as viewed in Fig. 2) and come to rest above the supports, then to cause the supports to be raised, and then to return the folders and supports to the positions shown in Fig. 2 ready for the presentation to the machine of another side or corner of the work. The rotation of the shaft 53 is caused by means of a treadle-controlled one-revolution clutch which will not be described, since the details of its construction form no part of the present invention and since any suitable means for imparting at will one revolution 15 to the shaft 53 may be employed.

The presser rod 21, which carries the plaiting tool 23, is held in a block 97 which is pivoted about a small rod 99 held in the arms of a yoke 98 the stem of which is adjustably 20 held in a carrier in the form of a split sleeve 101 by a pinch-screw 103. The block 97, as best shown in Fig. 2, has an upper arm extending over the yoke 98 and a lower arm extending beneath the yoke. A spring- 25 pressed plunger 105 carried by the upper arm and a stop-screw 107 carried by the lower arm tend at all times to hold the block 97, and with it the presser-rod 21 and plaiting tool 23, in the position with respect to the 30 pivot 99 shown in Fig. 2. It should be noted, however, that the plaiting tool may be pushed to the left at any time; and this is what occurs, as has been explained, during the folding operation.

The carrier 101 has integral with it a hub 109 loosely mounted on a rod 111 carried by upstanding lugs which project from the top plate of the machine. Also integral with the carrier 101 is a member 113 having 40 a bore to receive a headed plunger 115. The head of the plunger bears upon a stationary hardened plate 117: its stem, which extends up through the bore in the member 113, has check nuts 119 threaded upon its upper end; 45 and a coiled spring 121 tends at all times to cause the plunger to urge the carrier 101 upwardly about the axis of the rod 111, such upward movement being limited by a stop 123 carried by a tail 125 formed on the hub 50 109. Extending from the hub 109 and connected with the carrier 101 by a web 127 is an arm 129 to which is pivoted the upper end of a treadle-rod 131 so that, by exerting a downward pull upon the rod, the presser 21 55 and plaiting tool 23 may be brought down upon the work into the position shown in Fig. 5. When a piece of work is presented to the corner-folding mechanism it is desirable that the presser 21 should be brought down 60 upon the board 100 so as to press the work firmly down upon the work support 15 and should then be released by being raised slightly so as to permit the plaiting tool to be swung about its pivot 99 during the folding operation.

This could, of course, be accomplished by first depressing the treadle which is attached to the treadle rod 131 and then allowing the treadle to rise slightly and holding it in that position during the folding operation. In the present machine, however, depression and release of the treadle is all that is necessary first to bring the presser 21 down into the position shown in Fig. 5, then to raise it slightly so as to permit it to be pushed to the left during the folding operation, and finally to return it to the position shown in Fig. 2. To this end a lug which is integral with the web 127 has at its outer end a slot 133 through which extends the stem of a hardened block 135. A washer 137 and nuts 139 provide means for adjusting the stem to and holding it in any desired position in the slot. This block is normally in raised position and below it is a catch 141 underneath which it engages when the treadle rod 131 is pulled down. The catch is carried at the upper end of a smooth stem 143 which fits loosely in a vertical socket in a lever 145, said lever being pivoted at 147 to the frame 85 of the machine. A spring 149 tends at all times to urge the lever to swing in a clockwise direction. It is held normally in the position shown in Fig. 2 by reason of the fact that an inclined face on a lug which extends upwardly from the catch 141 is in contact with the block 135. The vertical position of the catch 141 with respect to the lever 145 may be varied by turning a thumb-screw 151, which is threaded into the top of the lever 100 and has two collars one above and the other below a forked extension on the catch. The catch 141 is adjusted into such a vertical position that, when the treadle has been depressed sufficiently to bring the rod 21 down into position to press the work firmly upon the support 15, as shown in Fig. 5, the upper face of the block will be slightly below the operative under face of the catch so that, when the treadle is released, the spring 121 will 105 raise the block slightly until it engages the catch, this upward movement serving to release the pressure of the rod 21 on the work, whereupon the rod may swing to the left, as shown in Fig. 6, during the folding operation. At the completion of the folding operation, or just before the completion of that operation, the upper portion of the lever 145 is swung to the left, as viewed in Fig. 2, to release the block 141 and permit the carrier 110 101 to rise, this swinging of the lever being brought about by contact with it of a screw 153 which is threaded through a boss carried by the folder 19 and held in adjusted position by a lock-nut.

Although not herein shown, the present machine is equipped with a treadle of the toe-and-heel type, the heel end being connected with the treadle rod 131 and the toe end with the treadle rod (not shown) which throws in 115 120 125 130

the one-revolution clutch. Assuming now that the piece of work comprises four straight edges and four rounded corners, the operation of the machine is as follows: A corner in the condition shown in Fig. 8, to the projecting margin of the cover 200 of which paste has been applied, is presented to the corner-folding mechanism, and then first the heel end and then the toe end of the treadle is depressed. Depression of the heel end brings the presser 21 and plaiting tool 23 into the position shown in Fig. 5 to press the work firmly against the work support, the block 135 being then slightly below the catch 141. When the toe end of the treadle is depressed, the heel end is released, with the result that the presser 21 and plaiting tool 23 rise slightly so as to be free to swing. The folder 19 now moves to the left beneath the plaiting tool 23, and folds the margin of the cover 200 over the board 100 in the manner shown in Fig. 6. During this folding movement the plaiting tool, under the influence of the spring-pressed plunger 105, is caused to drag over the inner face of the corner of the margin; and this dragging, in cooperation with the operation of the folder, forms evenly spaced puckers in the margin. At the same time the margin of the cover is gripped frictionally between the tool or member 23 and the folder 19 and pulled tightly about the edge of the board. Just before or at the moment the folder has completed its forward movement, the screw 153 strikes the lever 145 and releases the block 135, whereupon the plaiting tool rises to its normal inoperative position shown in Fig. 2. After the folder has completed the formation of the fold, it pauses while the work support 15 is moved upwardly to press the fold, as shown in Fig. 7. Thereafter the work support and the folder are returned to their normal, inoperative position, and the machine comes to rest. The remaining three corners are then folded in the same manner. If the piece of work is sufficiently small, or if the corner folding mechanism is sufficiently large, the folding of the corners may suffice also to fold the four straight portions. Otherwise the four straight portions are presented in succession to the straight-edge folding mechanism comprising the work support 27, edge guide 29 and folder 31, which operates exactly like the corner folding mechanism except that no plaiting tool is employed.

The paste used in this work tends to collect and harden on the under side of the folders 19 and 31 and to interfere with the proper operation of the machine. In order to overcome this difficulty a piece of moist, absorbent material 155, such as felt, is set in the edge guide 29 in position to wipe across the under face of the folder 31; and a similar piece 157 is similarly located with respect to the corner folder 19. By providing means

for moistening the under faces of the folders, the collection and hardening of paste upon them is obviated.

When square corners are to be produced it is customary to prepare the work as shown in Fig. 10 in which the boards 300 have the desired square corners while the corners of the covers have been cut off as shown to remove surplus material which would otherwise cause an undesirable bunch in the folded corners. In folding such a piece of work it is desirable first to fold the straight portion on one side of a corner, as shown in Fig. 11, and then to form a plait at or near the junction of the two margins prior to folding the straight portion which is located at the other side of the corner. In the present machine the straight edge-guide 29 is provided with two faces 157, 159 parallel to but offset from each other so that there is formed between their adjacent ends a shoulder 161. In folding a piece of work such as that shown in Fig. 10, the whole of one margin is first folded by presenting the work in the manner which has been described to the face 157 of the edge guide and throwing in the one-revolution clutch. The work is then in the condition shown in Fig. 11. The work adjacent to the corner is then presented to the face 159 of the edge guide in the manner shown in Figs. 12 and 13. The result of this presentation is to crumple the cover more or less adjacent to the corner and to form a pucker 163. One end of the folder 31 is alined with the shoulder 161; and when the one-revolution clutch is thrown in the pucker is pressed flat to form a sort of plait. The work is next turned ninety degrees, the margin on the other side of the corner presented to the straight face 157, and the one-revolution clutch thrown in to produce the result shown in Fig. 14. The operator then proceeds to pucker and plait the next corner, and so on until the entire margin of the cover is folded. In order to provide for right-hand and left-hand corners, with reference to the work when it is in the condition shown in Fig. 11, the edge guide 29 (see Fig. 1) is provided with two faces 159 which are offset from the face 157 and with two shoulders the faces of which are respectively alined, or substantially so, with the ends of the folder.

Throughout the specification, the edges of the cover which extend from one corner to another have, for convenience, been referred to as straight edges, although whether they are in every case straight is immaterial.

Having described my invention, what I claim as new and desire to secure by Letters Patent of the United States is:—

1. A machine for folding the covers of book cases which have straight edges and round corners, said machine having, in combination, round corner folding mechanism located at a given level, straight edge folding mecha-

nism located at a lower level, the two mechanisms being located and arranged to permit a straight edge and a round corner of a book case to be presented in succession to the mechanisms by an operator whose position remains unchanged.

2. A machine for folding the covers of book cases which have straight edges and round corners having, in combination, a cross-head, means for reciprocating the cross-head, two work supports carried by the cross-head, an edge guide and a folder each having a single straight face associated with one work support, an edge guide and a folder each having two faces arranged at an angle to each other and associated with the other work support, the construction and arrangement being such that a straight edge and a round corner of a book case may be placed in succession upon the work supports by an operator whose position remains unchanged, and means for reciprocating the folders.

3. A machine of the class described having, in combination, an edge guide having a pair of faces arranged to include an angle between them, a folder having a pair of faces arranged to include between them a smaller angle, and means for causing relative reciprocation between the folder and edge guide in a path which is parallel to a line connecting the apices in which the respective pairs of faces meet, said folder being held from lateral oscillation.

4. A machine of the class described having, in combination, an edge guide having two faces arranged to include an angle between them, a work support having a portion extending into the angle, a folder having two faces arranged to include between them a smaller angle, and means for causing relative movement between the work support and the folder first in a direction to cause the folder to overhang the support and then in another direction to cause approach of the folder and support, said folder being held from lateral oscillation.

5. A machine for folding the cover of a book at a corner thereof having, in combination, an edge guide having two faces arranged to include between them an angle substantially the same as that which is to be included between the two folded edges of the cover, a folder having two faces which include between them a smaller angle, means for producing relative movement between the guide and folder to form the fold, and means for pressing the fold, said folder being held from lateral oscillation.

6. A machine for folding the cover of a book at a corner thereof having, in combination, an edge guide having two faces arranged to include between them an angle substantially the same as that which is to be included between the folded edges of the cover, means for folding the corner progres-

sively beginning simultaneously at two points spaced from the corner, a tool adapted to act upon the corner in cooperation with the folding means to facilitate the formation of plaits, and means for pressing the fold.

7. A machine for folding the cover of a book at a corner thereof having, in combination, an edge guide having two faces arranged to include between them an angle substantially the same as that which is to be included between the folded edges of the cover, means for folding the margin at the corner progressively beginning at two points spaced from the corner, a member adapted to cooperate with the folder in the formation of plaits, and means for holding the member, during the folding operation, against the inner face of the margin in a locality opposite to that engaged by the folder.

8. A machine for folding the cover of a book at a corner thereof having, in combination, an edge guide having two faces arranged to include between them an angle substantially the same as that which is to be included between the folded edges of the cover, a folder having two faces which include between them a smaller angle, means for producing relative movement between the guide and folder for forming the fold, a plaiting tool adapted to act upon the corner during the folding operation, yielding means acting through the tool in opposition to the movement of the folder during the folding operation, and means for pressing the fold.

9. A machine for folding the corner of the cover of a book over the corner of the board to which the cover is attached having, in combination, a support for the work, an edge guide, a plaiting tool, a folder, means for causing the tool to press upon the board, means for moving the folder, and means coming into operation before the completion of the movement of the folder for raising the plaiting tool and holding it in position to drag over the inner face of the margin of the cover.

10. A machine for folding the cover of a book at a corner thereof having, in combination, a support for the work, a folder, means for operating the folder to form the fold, a combined work presser and plaiting tool, and means operating first to cause the combined member to force the work against the work support and then to release the member to permit the member to drag over the inner face of the margin of the cover during the operative movement of the folder.

11. A machine of the class described having, in combination, a support for the work, an edge guide having two faces one of which is offset with respect to the other to form a shoulder, a folder one end of which is substantially in register with the shoulder, and means for causing relative movement be-

- tween the folder and support first to bring the shoulder beneath the folder and then to cause movement of approach between the folder and the support.
- 5 12. A machine of the class described having, in combination, a support for the work, an edge guide having two faces one of which is offset with respect to the other to form a shoulder, a folder one end of which is substantially in register with the shoulder, and means for operating the folder and the support. 70
- 10 13. A machine of the class described having, in combination, a support for a piece of work comprising a rectangular backing of 75 comparatively stiff material over one margin of which the margin of a flexible cover has been folded and over the adjacent margin of which the adjacent margin of the cover is to be folded having, in combination, an edge guide having an offset portion to which the work may be presented to pucker a portion of the unfolded margin, and means for exerting pressure upon the puckered portion prior to folding the margin. 80
- 15 14. A machine for operating upon two margins of the cover of a book which lie at an angle to each other outside a sharp corner of the board to which the cover is attached having, in combination, means for folding one margin over the board, and means for thereafter puckering the cover adjacent the corner of the board preparatory to folding the remaining margin. 85
- 20 15. A machine for operating upon two margins of the cover of a book which lie at an angle to each other outside the edges of a sharp corner of the board to which the cover is attached having, in combination, 90 means for folding one margin over the board and means for thereafter forming a pucker in that portion of the folded margin which extends beyond one edge of the board and for pressing the pucker into a plait preparatory to folding the remaining margin. 95
- 25 16. A machine for operating upon two margins of the cover of a book which lie at an angle to each other outside the edges of the sharp corner of the board to which the cover is attached having, in combination, a support for the work, an edge guide having two faces one of which is offset with respect to the other to form a shoulder to which the partly folded margin of the cover may be presented in such manner as to form a pucker in the cover, a folder one end of which is substantially in register with the shoulder, means for causing relative movement between the support and the folder in a direction to cause the folder to overhang the pucker, and means for causing further relative movement between the same members in another direction to press the pucker into a plait. 100
- 30 17. A machine for operating upon two margins of the cover of a book which lie at an angle to each other outside the edges of the sharp corner of the board to which the cover is attached having, in combination, a support for the work, an edge guide having two faces one of which is offset with respect to the other to form a shoulder to which the partly folded margin of the cover may be presented in such manner as to form a pucker in the cover, a folder one end of which is substantially in register with the shoulder, means for moving the folder over the pucker, and means for causing relative movement of approach between the folder and the support to press the pucker. 105
- 35 18. A machine for operating upon two margins of the cover of a book which lie at an angle to each other outside the edges of the sharp corner of the board to which the cover is attached having, in combination, a support for the work, an edge guide having two faces one of which is offset with respect to the other to form a shoulder to which the partly folded margin of the cover may be presented in such manner as to form a pucker in the cover, a folder one end of which is substantially in register with the shoulder, means for moving the folder over the pucker, and means for causing relative movement of approach between the folder and the support to press the pucker. 110
- 40 19. A machine for folding the margin of a piece of flexible material to which paste has been applied having, in combination, a support for the material, a folder movable in a path to bend the margin of the material over the body portion thereof, and means located in the path of movement of the folder for supplying moisture to a surface of said folder. 115
- 45 20. A machine for forming a fold in the margin of a piece of flexible material to which paste has been applied having, in combination, a support for the material, a movable folder, a support for the folder and a piece of moist absorbent material mounted in the folder support and arranged to engage one face of the folder. 120
- 50 21. Mechanism for folding the margin of a book-cover or similar article at a corner thereof having, in combination, an edge guide having divergent faces the curve at the junction of which corresponds to the curve desired on the finished corner of the cover, a folder having divergent faces, the curve at the junction of which is of smaller radius than that at the junction of the faces of the edge guide, a work support, and means for causing relative movement between the folder and the work support first in a direction to cause the folder to overhang the work support and then in a direction to cause approach of the folder and work support. 125
- 55 22. Mechanism for folding the margin of a book-cover or similar article having, in combination, an edge guide having an outline 130

- corresponding to the outline desired on the corner of the finished cover, a work support a portion of which has a similar outline, a folder having divergent faces, a tool adapted to cooperate with the folder to facilitate the formation of plaits said tool being normally raised above the work support sufficiently to permit a book-cover to be presented beneath it, means for moving the tool down into the path of the folder, means for moving the folder over the edge guide first to force the inner face of the margin of the cover against the tool and then to bend the margin down over the body portion of the cover, the inner face of the margin dragging over the contacting face of the tool during this bending, and means for thereafter causing relative movement of approach between the support and the folder.
23. Mechanism for folding the margin of a book-cover or similar article at a corner thereof having, in combination, an edge guide having divergent faces joined by a curved face the curvature of which corresponds to the curve desired on the finished corner of the cover, a folder having divergent faces joined by a curved face, the curve of which is of smaller radius than that of the edge guide, a work support shaped to extend into the space defined by the edge guide, a tool adapted to cooperate with the folder to facilitate the formation of plaits, said tool being normally raised above the work support sufficiently to permit the corner of a book-cover to be laid on the work support with the margin of the cover overlying the edge guide, means for moving the tool down into the path of the folder, means for moving the folder over the edge guide, whereby the margin is first forced against the tool and then bent down over the body portion of the cover, and means for causing relative movement of approach between the folder and the work support to press the bent over margin into place.
24. Mechanism for folding the margin at the corner of a book-cover or similar article having, in combination, a work support, an edge guide, a folder, means for moving the folder over the edge guide and the work support to form the fold, means for causing relative movement of approach between the folder and support to press the fold, a tool adapted to cooperate with the folder to facilitate the formation of plaits, and means for continually urging the tool into the path of movement of the folder during the movement of the folder over the edge gage and work support.
25. A machine for folding the covers of book cases which have straight edges and round corners, said machine having, in combination, corner folding mechanism including an edge guide having two faces arranged at an angle to each other and a folder also having

two faces arranged at an angle to each other, straight edge folding mechanism including a straight-faced edge guide and a straight-faced folder, said mechanisms being located and arranged to permit a straight edge and a corner of a book case to be presented in succession to the mechanisms by an operator whose position remains unchanged, and means for operating the mechanisms.

26. The method of folding book covers which comprises folding in succession two adjacent corners and then folding the margin which extends between them.

27. A machine of the class described having, in combination, a support for the corner portion of a piece of sheet material, means for folding the margin of said corner portion at a single operation, a co-operating tool adapted to facilitate the formation of evenly spaced plaits in the folded margin, said tool being movably mounted in the path of movement of the folding means, and yielding means for causing the tool to oppose the movement of the folder during the folding operation.

28. A machine of the class described having, in combination, a support for the corner portion of a piece of work, a folder movable to fold the margin of the corner portion at a single operation, a co-operating member for engaging the inner face of the corner portion, and yielding means acting in opposition to the folding movement of the folder for holding the member in contact with the inner face of the margin.

29. A machine of the class described having, in combination, a support for the corner portion of a piece of work, a folder movable to fold the margin of the corner portion at a single operation, a co-operating member for engaging the inner face of the corner portion, yielding means acting in opposition to the folding movement of the folder for holding the member in contact with the inner face of the margin, and means for pressing the fold.

30. A machine for folding the cover of a book at a corner thereof having, in combination, an edge guide having a curved portion the curvature of which corresponds to the desired curvature at the corner of the finished cover, a folder having a curved portion the curvature of which is more abrupt than that of the corresponding portion of the edge guide, and means for producing relative movement between the folder and the edge guide to fold the corner of the cover.

31. A machine for folding the cover of a book at a corner thereof having, in combination, an edge guide having a curved portion the curvature of which corresponds to the desired curvature at the corner of the finished cover, a folder having a curved portion the curvature of which is more abrupt than that of the corresponding portion of the edge

guide, means for producing relative movement between the folder and the edge guide to fold the corner of the cover, and a member adapted to cooperate with the folder to facilitate the formation of evenly spaced plaits in the margin.

32. A machine for folding the cover of a book at a corner thereof having, in combination, an edge guide having a curved portion 10 the curvature of which corresponds to the desired curvature at the corner of the finished cover, a folder having a curved portion the curvature of which is more abrupt than that of the corresponding portion of the edge 15 guide, means for producing relative movement between the folder and the edge guide to fold the corner of the cover, a member adapted to cooperate with the folder to facilitate the formation of evenly spaced plaits 20 in the margin, and yielding means for urging the member toward the folder.

33. A machine for folding the margin of the cover of a book at a corner thereof having, in combination, a support for the work, 25 a folder, the operative edge of which comprises diverging faces, said folder being held from oscillation and adapted to fold the margin at the corner over the body portion of the work at a single operation, and a member 30 located in the path of movement of the folder adapted to co-operate with the folder during the folding operation to facilitate the formation of evenly spaced plaits.

34. A machine for folding the margin of 35 a piece of work at a round corner thereof in a single operation having, in combination, means for bending up the margin, a folder having a recess in its forward edge, a member adapted to cooperate with the recessed 40 edge of the folder to facilitate the formation of evenly spaced plaits in the margin, said folder and member having opposed operative faces, and means for causing the margin to be gripped frictionally between said faces 45 and, while so gripped, laid over upon the body portion of the work.

35. A machine for folding the margin of 50 a piece of work at a round corner thereof having, in combination, a folder held from lateral oscillation movable over the body portion of the work, a member adapted to cooperate with the folder to facilitate the formation of plaits in the margin of the work, and means for normally holding the member 55 yieldingly adjacent to the corner.

36. A machine for folding the margin of a piece of work at a round corner thereof having, in combination, a folder for engaging 60 the outer face of the margin and bending the margin over the body portion of the work, a member adapted to cooperate with the folder to facilitate the formation of plaits, and means for causing the operative 65 face of the member to pass progressively

over the inner face of the margin during the folding operation.

37. A machine for folding the margin at the corner of a cover over the rounded corner of a backing having, in combination, a 70 folder movable over the body portion of the work to fold the margin, a member adapted to cooperate with the folder to facilitate the formation of plaits, and yielding means for holding said member normally in the path of 75 movement of the folder and for permitting movement of said member during the folding operation in a direction to take it out of said path.

38. A machine for folding the margin of a 80 cover over the rounded corner of a backing having, in combination, a folder movable over the backing to fold the margin and a cooperating member adapted to facilitate the formation of evenly spaced plaits in the margin, said member being located in the path 85 of movement of the folder, and yielding means for opposing movement of the member in a direction away from the folder whereby the margin is gripped frictionally between the operative faces of the member and the folder and drawn about the rounded corner of the backing.

39. A machine for folding the margin of a 90 cover over the rounded corner of a backing having, in combination, a reciprocating folder movable over the body portion of the work, and a member adapted to cooperate with the folder to facilitate the formation of evenly spaced plaits, said member being 95 located in the path of movement of the folder and having a portion extending above the folder.

40. A machine for folding the margin of a 100 cover over the rounded corner of a backing having, in combination, a folder movable over the body portion of the work, and a member adapted to cooperate with the folder to facilitate the formation of evenly spaced plaits, said member being located in the path 105 of movement of the folder and having a portion extending above the folder and adapted to overhang the folder during the folding operation.

41. A machine for folding the margin of a 110 cover over the rounded corner of a backing having, in combination, a support for the corner portion of the work, means for imparting a bend to the margin, a folder, a member adapted to cooperate with the folder 115 to facilitate the formation of evenly spaced plaits in the margin, said member being normally located in the path of movement of the folder, and means for causing the folder first to press a portion of the margin against the member and then to move the margin progressively beneath the member and lay it down upon the body portion of the work.

42. A machine for folding the margin of a 120 cover over the rounded corner of a backing 125

having, in combination, a support for the corner of the work, means for bending up the margin, a tool having a plurality of ribs on its operative face, and means for folding the margin over the body portion of the work and at the same time dragging the margin over the face of the tool.

43. A machine for folding the margin at the corner of the cover of a book case over the round corner of a board thereof having, in combination, a support for the work, a folder movable over the board to fold the margin of the cover, a member adapted to cooperate with the folder to facilitate the formation of evenly spaced plaits in the margin, yielding means for holding the member normally in the path of movement of the folder, and means including the yielding means for permitting the member to rise during the folding operation so that the folder may move beneath it.

44. A machine for folding the margin at the corner of the cover of a book case over the round corner of a board thereof having, in combination, a folder, a member located in the path of movement of the folder and adapted to cooperate with the folder in the formation of plaits in the margin, and means for causing the folder and the member to move at the same time and, while moving, to grip and bend over the margin.

45. A machine for folding the margin at the corner of the cover of a book case over the round corner of a board thereof having, in combination, an edge guide having two faces arranged to include between them an angle substantially the same as that which is to be included between the two folded edges of the cover adjacent to the round corner, a folder having two faces which include between them a smaller angle, and means for reciprocating the folder and for holding it from lateral oscillation.

46. A machine for folding the margin at the corner of the cover of a book case over the rounded corner of a board thereof having, in combination, a support for the corner portion of the work, a folder, means for moving the folder over the board and for preventing the folder from oscillation during said movement, a member adapted to cooperate with the folder in the formation of plaits, said member being located in the path of movement of the folder and mounted for movement during the folding operation, and means for pressing the fold.

47. A machine for folding the margin at the corner of the cover of a book case over the rounded corner of a board thereof having, in combination, a support for the corner portion of the work, a folder, means for moving the folder over the board and for preventing the folder from oscillation during said movement, a member adapted to cooperate with the folder in the formation of plaits, said member

being located in the path of movement of the folder and mounted for movement during the folding operation, means for causing the margin to be held against the folder by the member and for causing the member to move with the folder, and means for pressing the fold.

48. A machine for folding the margin at the corner of the cover of a book case over the rounded corner of a board thereof having, in combination, a support for the corner portion of the work, a folder movable in a straight path over the support, and a member adapted to cooperate with the folder in the formation of plaits, said member being located in the path of movement of the folder and movable with the folder during the entire folding operation.

49. A machine for folding the margin at the corner of the cover of a book case over the rounded corner of a board thereof having, in combination, a work support, a movable folder, a yieldingly mounted member adapted to cooperate with the folder in the formation of plaits, said member being located in the path of movement of the folder, and means for causing the folder to press the margin against the member and to move the member during the folding operation.

50. A machine for folding the margin at the corner of the cover of a book case over the rounded corner of a board thereof having, in combination, a work support, a movable folder, a yieldingly mounted pivoted member adapted to cooperate with the folder in the formation of plaits, said member being located in the path of movement of the folder, and means for causing the folder to press the margin against the member and to swing the member about its pivot during the folding operation.

51. A machine for folding the margin at the corner of the cover of a book case over the round corner of a board thereof having, in combination, a substantially flat work support, a folder reciprocable in a straight path substantially parallel to the surface of the support, a member adapted to cooperate with the folder in the formation of evenly spaced plaits in the margin, said member being normally held above the support, means for bringing the member down upon the work and for bending up the margin into a position between the member and the folder, and means for causing the folder to force the margin against the member so as to grip it frictionally and to fold the margin over the board.

In testimony whereof I have signed my name to this specification.

PERLEY R. GLASS.
